UNITED STATES PATENT OFFICE.

PATRICK H. MURRAY, OF PARKER CITY, PENNSYLVANIA.

METHOD OF HEATING OIL-WELLS.

SPECIFICATION forming part of Letters Patent No. 239,975, dated April 12, 1881.

Application filed March 15, 1880. (No model.)

To all whom it may concern:

Be it known that I, PATRICK H. MURRAY, of Parker City, in the county of Armstrong and State of Pennsylvania, have invented certain new and useful Improvements in Devices for Heating Oil-Wells; and I do hereby declare that the following is a full, clear, and exact description of the invention, which will enable others skilled in the art to which it appertains to make and use the same, reference being had to the accompanying drawings, and to letters of reference marked thereon, which form a part of this specification.

My invention relates to an improved process and the devices for heating oil-wells for the purpose of melting the paraffine or other substances which obstruct the flow of oil. Heretofore this has been accomplished by hot water or steam, which have been found to be objectionable, the water requiring too much power to pump it out of the well, and the steam, even when superheated, condensing, and thus depositing water in the bottom of the well.

The object of my invention is to produce in the wells the required heat without the above-named objections. I accomplish this by introducing heated air directly upon the oil and the paraffine at the bottom of the well by suitable means, as hereinafter described, and as shown in the drawings, in which—

Figure 1 is a side elevation of a steam-heater and an air-pump with requisite pipes. Fig. 2 is a vertical longitudinal section of the heater and pump. Fig. 3 is an end view of a steam-heater having a number of air-pipes. Fig. 4 is an end view and a sectional view of one of the heads of the air-pump cylinder. Fig. 5 illustrates the manner of inserting the hot-air pipe in an oil-well.

40 A represents a steam-chest and heater, to be supplied with steam through a pipe, *a*, connected with a steam-generator.

B represents an air-pump, provided with a piston, *b*, and piston-rod *b'*, connected with the operating power. Each end of the pump-cylinder is provided with a hinged valve, *c*, adjusted over an opening to admit air into the cylinder as the piston moves from the opening, and to close the opening as the piston returns.

50 An air-pipe, *d*, is attached at each end to the pump-cylinder, communicating with the air-

chamber near the ends of the cylinder. This pipe is provided with check-valves *c' c'*, adjusted to open to allow the passage of air from the pump and to close to prevent the return of the air from the pipe into the pump. This pipe is connected in the middle with a pipe, *d'*, which is extended through the heater and downward into the oil-well. This air-pipe may be returned back and forth through the heater, as shown in Fig. 2 of the drawings, and then extended down the well to increase the heat of the air in the pipe before being forced into the well; and any required number of pipes may be employed and extended through the heater into the well to increase the quantity of the hot air in the well. The heater is provided with a drainage-cock, as shown at *d''*.

The heater and air-pump may be placed at any convenient distance from the oil-well. The hot-air pipe is inserted within the casing *C* with the tubing *D*, as shown in Fig. 5 of the drawings, thus imparting to the oil-tube warmth sufficient to prevent the liability of the paraffine from adhering to the walls of the tube, and facilitating the flow of oil through the well-tube, while the hot air is forced directly upon the oil and paraffine at the bottom of the well. The heater being supplied with steam and the pump put in operation, the air is forced through the pipe *d* into the pipe *d'*, and after being sufficiently heated is forced downward through the extended pipe *d'* directly upon the oil and paraffine at the bottom of the well-tube, thus melting the paraffine or other gummy substances, preventing the obstruction and facilitating the flow of the oil. In the process of thus forcing hot air through the oil some gas will be produced, which may be utilized for fuel or lights.

What I claim as new, and desire to secure by Letters Patent, is—

1. The improved method or process of preventing obstructions to and of facilitating the flow of oil in an oil-well with hot air by forcing air through a heater in which the requisite degree of heat is imparted to the air, and conducting and forcing the heated air downward to and in direct contact with the oil and paraffine at the bottom of the well, substantially as set forth.

2. The devices herein described, and shown

in the drawings, as arranged and combined for heating an oil-well, consisting of the heating-chamber A, the air-pump B, and the air-pipes *dd'*, connected with the air-pump and extended 5 back and forth in the heating-chamber, and thence downward in the well-casing C to the bottom of the well, substantially as described.

In testimony that I claim the foregoing as my own invention I affix my signature in presence of two witnesses.

PATRICK H. MURRAY.
